EP	0867724	9/1998
EP	1152244	11/2001
EP	1680225	7/2006

Primary Examiner — Manpreet Matharu*Assistant Examiner* — Suzanne Tisdell(74) *Attorney, Agent, or Firm* — Edward J. Baba; Bozicevic, Field & Francis LLP(57) **CLAIM**

The ornamental design for print tape cartridge, as shown and described.

DESCRIPTION

FIG. 1 is a top perspective view of a print tape cartridge; FIG. 2 is a bottom perspective view of the print tape cartridge;

FIG. 3 is a top view of the print tape cartridge;

FIG. 4 is a bottom view of the print tape cartridge;

FIG. 5 is a front view of the print tape cartridge;

FIG. 6 is a back view of the print tape cartridge;

FIG. 7 is a first side view of the print tape cartridge; and,

FIG. 8 is a second side view of the print tape cartridge.
